F. MANKEY.

MOLDING.

No. 17,226.

Patented Mar. 29, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,226, dated March 29, 1887.

Application filed February 28, 1887. Serial No. 229,265. Term of patent 7 years.

To all whom it may concern:

Be it known that I, FREDERICK MANKEY, of Williamsport, Lycoming county, Pennsylvania, have invented and produced a new and original Design for Trims or Moldings, of which the following is a specification, reference being had to the accompanying photograph, forming part hereof.

One edge of the trim is straight, as shown at 10 A. Upon the other edge appears the following configuration: a large scallop, B, and adjacent thereto a straight portion, C. At right angles to said straight portion C is a straight portion, D. Adjacent to said straight portion 15 D is a straight portion, E, parallel to the straight portion C. Adjacent to the straight portion E is a small scallop, F. Adjacent to the scallop F is a straight portion, G, on a line with the straight portion E. Adjacent to the straight 20 portion G is a straight portion, H, parallel to the straight portion D. Finally, adjacent to

the straight portion H is a straight portion, I, on a line with the straight portion C. Upon the face of the molding appear the annular depressions J and the semi-annular depressions K.

The above described configuration upon the edge of the molding is repeated along said edge, as shown.

I claim:

The design for a trim or molding, substantially as herein shown and described, which consists in the configuration comprising the scallop B, scallop F, and straight portions C D E G H I on the edge of said trim, and on 35 the face thereof the annular depression J and semi-annular depression K.

FREDERICK MANKEY.
